PAPER TOWELING

Gordon D. Thomas, Neenah, Wis., assignor to Kimberly-Clark Corporation, Neenah, Wis.

Filed Mar. 9, 1973, Ser. No. 339,823

Term of patent 14 years

Int. Cl. D5—06

U.S. Cl. D59—2 A

FIG. 1

FIG. 2

FIG. 1 is a plan view of a paper toweling showing my own design; and

FIG. 2 is an enlarged fragmentary view thereof.

I claim:

The ornamental design for a paper toweling, as shown.
